UNITED STATES PATENT OFFICE.

HARRY WEARNE, OF RIXHEIM, GERMANY.

DESIGN FOR WALL-PAPER.

SPECIFICATION forming part of Design No. 32,023, dated December 19, 1899.

Application filed November 22, 1899. Serial No. 737,957. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a plan view of a strip of wall-paper embodying the features of my design.

The leading features of the design consist in a series of panels supported by ornamental borders and a bouquet of flowers in the central panel, from which bouquet trail floral sprays so crossed that they form a series of loops.

The minor features of the design consist in the rope-like decoration of the borders, a knot tying the ends of the stems in the bouquet, ²⁰ and the floral sprays appearing at intervals upon the borders.

Having thus described my invention, I claim as new and desire to secure by Letters Patent—

The design for wall-paper as herein shown and described.

HARRY WEARNE.
